[57] CLAIM

The ornamental design for a ball puzzle, as shown and described.

DESCRIPTION

FIG. 1 is a top plan view of a ball puzzle in an unsolved position showing my new design;

FIG. 2 is a bottom plan view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is another top plan view thereof showing the outer transparent ball rotated to a different position with respect to the inner opaque ball; and,

FIG. 8 is a front elevational view thereof.

The pentagonal graphics are applied to an inner opaque sphere member; each pentagonal graphic having a circular gap therein. The paired circular graphics are applied to an outer transparent shell member.
